UNITED STATES PATENT OFFICE.

CHARLES E. BERTELS, OF WILKES-BARRÉ, PENNSYLVANIA.

DESIGN FOR A COVER FOR DINNER-PAILS.

SPECIFICATION forming part of Design No. 21,366, dated March 8, 1892.

Application filed December 31, 1891. Serial No. 416,733. Term of patent 7 years.

To all whom it may concern:

Be it known that I, CHARLES E. BERTELS, a citizen of the United States, residing at Wilkes-Barre, in the county of Luzerne and State of Pennsylvania, have invented and produced a new and original Design for Covers for Dinner-Pails, of which the following, reference being had to the accompanying drawings, forming a part thereof, is a specification.

My design for a bottle or reservoir cover for dinner-pails is fully represented in the accompanying drawings, to which reference is made.

15 The dinner-pail cover to which my invention relates is of the kind constructed to hold liquids, as tea, coffee, &c., and is designed to fit within the top of the dinner-pail within which the solid food is contained.

20 1 represents the side walls, and 2 the end walls, of my cover or "bottle," which are each of straight vertical contour, whereby, in conjunction with the customary straight vertical sides of the body portion of the pail, a uniform square appearance is imparted to the complete pail.

3 represents a circumferential bead, which when the cover or bottle is in position rests upon the top edge of the body of the pail to support the cover in position.

30 The top and bottom portions 4 of the cover or bottle are of flat or horizontal straight contour, as shown. 5 represents a central flange-guarded opening in the top, through which the liquid is supplied to and poured from the 35 cover or bottle. This flange-guarded opening may be closed by a cover or drinking-cup 6. The upper portion of the side and end walls adjacent to the top of the cover are somewhat curved or rounded, as at 7.

40 What I claim as my design is—

The design for a cover or bottle for dinner-pails, herein shown and described.

In testimony whereof I affix my signature in presence of two witnesses.

CHARLES E. BERTELS.
